Theophilus Charles Eberhardt,
By his Attorneys
Baldwin, Davidson & Wright.

UNITED STATES PATENT OFFICE.

THEOPHILUS CHARLES EBERHARDT, OF CUERO, ASSIGNOR TO HERMAN ELSAS, OF DALLAS, TEXAS.

PAPER HOLDER AND CUTTER.

SPECIFICATION forming part of Letters Patent No. 392,668, dated November 13, 1888.

Application filed August 13, 1888. Serial No. 282,618. (No model.)

To all whom it may concern:

Be it known that I, THEOPHILUS CHARLES EBERHARDT, a citizen of the United States, residing in the town of Cuero, in the county of 5 De Witt and State of Texas, have invented certain new and useful Improvements in a Combined Paper Holder and Cutter, of which the following is a specification.

My invention relates to that class of paper holders and cutters in which the paper is drawn through a holder and severed at any desired point. Its objects are to secure a cheap, simple, durable, efficient, and easily-manipulated apparatus capable, if required, of holding 15 several sheets of the same or different widths, which can be fed side by side and cut to the requisite length, leaving a projecting edge behind the cutter to afford ready means of drawing out the succeeding sheet.

20 The accompanying drawings show so much of my improved machine as is necessary to illustrate the invention claimed.

Figure 1 represents a plan or top view, and Fig. 2 an end view, thereof.

25 Bases or supports A A' are shown as provided, preferably, with suitable holes, a, to permit of their being secured to a counter, table, or other support in usual well-known ways. The main or central holding-bar consists, preferably, of a flat blade, B, having its ends b turned up at right angles thereto. This blade is preferably secured to the bases in such manner that they project slightly—say half an inch—beyond its ends, for a purpose 30 hereinafter described.

35 The knife C consists of a flat sharp-edged blade, the ends c of which are bent at right angles to its surface and secured to the upright ends b of the central holder, so that the 40 blade lies transversely to the holder and vertically over it.

45 Outside holding-bars, D D', preferably consisting of flat rectangular bars, are arranged parallel with and on each side of the central bar, in the same horizontal plane. These bars are held down upon, but permitted to slide over, the bases A A', by means of flat-headed pins E passing through right-angled slots d in the bars. That part of the slots nearest the 50 center is transverse to the edge of the bar, while the other portion is parallel therewith,

By this means the outside bars can be moved away from the center one and held in that position by sliding them endwise, so that the pins take into the longitudinal parts of the 55 slots.

Knobs P P' on the outside bars afford means for moving them, as well as serving as points of attachment for spiral springs G G', which extend from one to the other, preferably outside the upright parts b of the central bar. These springs tend to draw the outside bars together to clamp the paper between them and the central bar when free to move and thus hold the paper with a firm but elastic pressure. 60 65

The central bar, preferably, is covered with leather, cloth, felt, or other pliable material to secure a soft yielding surface, over which the paper may be drawn with sufficient friction without being torn.

70 In operation an outside bar—one or both—is drawn away from the central bar and the paper passed between them and clamped, as above described. Separate strips may be fed in from opposite sides of the bar or from the same side, as desired. The strip is drawn out the desired length and torn off by a quick jerk against the edge of the cutter, as usual, leaving always a projecting end convenient 75 for grasping the next time.

80 The paper is preferably drawn from a roll or rolls placed in a bracket or box beneath the table or mounted on a roller or spindle located in any convenient place.

Having thus fully described the construction and operation of my improved combined paper holder and cutter, what I claim therein as new and of my own invention, and desire to secure by Letters Patent, is—

85 1. The combination, substantially as hereinbefore set forth, of the base-pieces, the central holding-bar secured thereto, its upright end pieces, and the cutter secured thereto.

90 2. The combination, substantially as hereinbefore set forth, of the base-pieces, the central holding-bar, the outside holding-bars, their slots and guide-pins, and the spiral springs connecting them to hold them against the central bar, as described.

95 3. The combination, substantially as hereinbefore set forth, of the central holding-bar, contiguous holding-bars arranged on oppo-

site sides thereof, parallel therewith, and in the same horizontal plane, springs clamping the holding-bars against the bar, and a cutter or knife bar parallel with the holding-bars, 5 with its edge presented thereto.

4. The combination, substantially as hereinbefore set forth, of the central holding-bar, its pliable covering, a holding-bar parallel

therewith, and springs holding the bars together with a yielding or elastic connection. 10

In testimony whereof I have hereunto subscribed my name.

THEOPHILUS CHARLES EBERHARDT.
